United States Patent [19]

Leman

[11] Patent Number: **Des. 401,926**
[45] Date of Patent: ****Dec. 1, 1998**

[54] **PERSONAL COMPUTER HOUSING FACE PLATE**

D. 381,327 7/1997 Su D14/115

[75] Inventor: **Michael V. Leman**, Eagle, Id.

Primary Examiner—Freda Nunn
Attorney, Agent, or Firm—Craig M. Korfanta

[73] Assignee: **Micron Electronics, Inc.**, Nampa, Id.

[57] CLAIM

[**] Term: **14 Years**

I claim the ornamental design for a personal computer housing face plate, as shown and described.

[21] Appl. No.: **78,423**

DESCRIPTION

[22] Filed: **Oct. 24, 1997**

FIG. 1 is a 3-border perspective view of a personal computer housing faceplate which shows my new design;

[51] LOC (6) Cl. **14-02**

FIG. 2 is a front elevation view thereof;

[52] U.S. Cl. **D14/115**

FIG. 3 is a right side elevation view thereof; and,

[58] Field of Search D14/100, 102,
D14/107-109, 115, 137, 156, 217, 257,
258; D10/103; D13/162, 184, 199, 164,
177; 312/223.2; 361/600, 622, 724-728;
428/99

FIG. 4 is a left side elevation view thereof.

The housing is shown in broken lines in the views for illustrative purposes only and forms no part of the claimed design.
